UNITED STATES PATENT OFFICE.

ADOLF K. F. HARNAPP, OF WEST NEW YORK, NEW JERSEY, ASSIGNOR TO HARNAPP COMPANY, INC., OF WEST NEW YORK, NEW JERSEY, A CORPORATION OF NEW YORK.

DESIGN FOR LACE TRIMMING FOR A DOILY OR THE LIKE.

Application filed May 27, 1927. Serial No. 22,197. Term of patent 3½ years.

To all whom it may concern:

Be it known that I, ADOLF K. F. HARNAPP, a citizen of the United States, residing at West New York, county of Hudson, and State of New Jersey, have invented a certain new, original, and ornamental Design for Lace Trimming for a Doily or the like, of which the following is a specification, reference being had to the accompanying drawing, forming part thereof.

The figure is a plan view of one end of lace trimming constituting my new design, the opposite end being a repetition.

I claim:

The ornamental design for lace trimming for a doily or the like, as shown and described.

ADOLF K. F. HARNAPP.
